(57) **CLAIM**

The ornamental design for a vehicle taillamp, as shown and described.

DESCRIPTION

FIG. 1 is a perspective view of a vehicle having a vehicle taillamp in accordance with an embodiment of the present invention;

FIG. 2 is a side view of the taillamp shown in FIG. 1;

FIG. 3 is another side view of the taillamp shown in FIG. 1; and,

FIG. 4 is a front view of the exterior of the taillamp shown in FIG. 1.

The bottom and rear views of the taillamp are not part of the claimed design. The broken lines for the attachment portions of the taillamp to a vehicle illustrate the environment of the design and are not part of the claimed design.
